UNITED STATES PATENT OFFICE.

HERBERT A. BRIGGS, OF NEW YORK, N. Y.

TYPE-WRITING MACHINE.

No. 895,720.

Specification of Letters Patent.

Patented Aug. 11, 1908.

Original application filed August 22, 1904, Serial No. 221,756. Divided and this application filed January 7, 1907.
Serial No. 351,257.

To all whom it may concern:

Be it known that I, HERBERT A. BRIGGS, a citizen of the United States, residing at New York city, in the borough of Manhattan and 5 State of New York, have invented certain new and useful Improvements in Type-Writing Machines, of which the following is a specification.

This invention relates to typewriting machines, and has particular reference to an improved device or attachment for typewriting machines controlled through the medium of a key at the key board and comprising means for printing an auxiliary character such as an 10 underscoring or canceling mark.

To this end the invention primarily comprises an auxiliary character or characters, a key for operating the same, and means whereby the movement of the platen or of the type 20 action, or of both, may be utilized to sweep the auxiliary character or characters over the paper in the direction of letter spacing, thus enabling the operator to quickly and neatly print an entire line or any portion thereof. 25 Hence, where the auxiliary character consists of an underscoring mark an entire line or any part of a line may be underscored without the loss of time and without the untidiness of the common methods of under- 30 scoring employed in the ordinary forms of typewriting machines.

With these and other objects in view, which will readily appear as the nature of the invention is better understood, the same con- 35 sists in the novel construction, combination and arrangement of parts hereinafter more fully described, illustrated, and claimed.

The essential features of the invention involved in carrying out the foregoing objects 40 are necessarily susceptible to a wide range of structural modification, and also to a wide range of application to different kinds of typewriting machines, without departing from the scope of the invention, one of the 45 preferred embodiments of which is shown in the accompanying drawings, in which:—

Figure 1 is a side elevation of a special form of machine in connection with which my invention may be used to advantage. Fig. 2 50 is a diagrammatic sectional view of the special machine shown in Fig. 1, and illustrating more clearly the normal inoperative position of the auxiliary character. Fig. 3 is a detail elevation of the rear part of the traveling

type carriage, showing a practical manner of 55 mounting the auxiliary character. Fig. 4 is a diagrammatic view of the auxiliary character operating device shown in its inoperative relation to the platen and paper thereon. Fig. 5 is an enlarged detail elevation of the 60 auxiliary characters preferably employed,— an underscoring device and a canceling device. Fig. 6 is an enlarged detail sectional view on the line 6—6 of Fig. 4.

Like references designate corresponding 65 parts in the several figures of the drawings.

My invention is capable of general application to any make of typewriting machine embodying a platen and wherein the movement of the platen or of the type action, or 70 both, may be utilized in operating the device. Hence, the device is applicable to standard typewriting machines having stationary type actions and traveling platens or vice versa, but, inasmuch as the improve- 75 ments forming the subject matter of this application possess special utility in their application to the special form of machine disclosed in my allowed application, Serial No. 221,756, filed August 22, 1904, the same are 80 illustrated in the drawings in connection with a machine of that construction. In this special machine, a distinctive feature thereof resides in the combination of a traveling type carriage carrying the printing in- 85 strumentalities, and a traveling paper carriage carrying the platen, its auxiliaries, and also carrying a ribbon mechanism, the purpose of this combination being to provide means for dividing, between the two car- 90 riages, the travel necessary to go from the final letter of one printed line to the initial letter of the next printed line, thus effecting a very great saving in time and space re- 95 quired for this purpose.

Referring to the illustrated embodiment of the invention shown in the drawings, the numeral 1 designates the main horizontal base portion of the machine, which base portion is provided, preferably at the back 100 thereof, with an upright base section 2 having thereon at the top the opposite parallel track rails 3 supporting the front and rear traveler rollers 4 and 5, respectively, of the frame 6 of the traveling paper carriage: 105 This paper carriage is designated in its entirety by the numeral 7 and comprises the carriage carrying the paper handling and

supporting devices, including the platen P, with which platen is associated a shift key mechanism, (not claimed herein) for raising and lowering the same to effect upper and lower case printing as will be well understood by those familiar with the art. In addition to these instrumentalities the paper carriage supports and carries the entire ribbon mechanism. This ribbon mechanism embodies in its general organization oppositely arranged ribbon spools S arranged on suitable supports, and disposed obliquely in rear of the platen and held at a higher elevation than the axis of the latter, so that the 15 ribbon R assumes an inclined position. The ribbon winds and unwinds from one support to the other, according to which is fast or loose with its operating gear, and is arranged, through the medium of suitable 20 guides, to pass entirely about the paper carriage frame, and to have its operative portion extend longitudinally of the platen in front thereof, as may be plainly seen from the drawings. Furthermore, the advantage 25 of the oblique disposition of the spools and the inclination of the end runs of the ribbon is that the path of the ribbon is brought above the axis of the platen out of the way of the platen shaft, and also permits the 30 operator to inspect the work, while at the same time the operative portion of the ribbon is disposed in a coöperative relation to the auxiliary character or characters forming a part of the present invention. The actuating means for the ribbon spools comprises suitable gearing controlled through the movement of the paper carriage, substantially as and in the manner fully set forth in the other application aforesaid.

40 The main horizontal base portion 1 of the machine has suitably supported therein the front and rear rail sections or members 8 and 9 on which travel the front and rear rollers 10 and 11 of the frame 12 of the traveling 45 type or type action carriage. This latter carriage is designated in its entirety by the reference number 13 and comprehends the traveling carriage with the printing instrumentalities supported and carried thereby, 50 i. e. the type action which includes the key and operating devices.

As set forth in the other application aforesaid, the two carriages 7 and 13 have independent traveling supports upon separate 55 parts of the base, and the paper carriage 7 is arranged in a higher plane than the type carriage 13 to insure perfectly visibility of writing, while at the same time presenting the most favorable arrangement for the effective working of my invention. Also, as set forth in said application, the two carriages are coupled together for movement in unison, but in opposite directions, whereby a division of the travel may be properly apportioned to each carriage to effect a saving

in time and space required to go from the final letter of one printed line to the initial letter of the next printed line.

The auxiliary character preferably employed consists of a revoluble wheel arranged 70 to print a continuous line across the page for underscoring purposes, and in the drawings I have shown such a device and also an additional auxiliary character consisting of a revoluble wheel carrying a canceling character 75 which may consist of any suitable canceling mark, one of said auxiliary characters being operative when the paper carriage is in lower case position and the other when the carriage is in upper case position. 80

The operating mechanism for the specific forms of auxiliary characters illustrated herein comprises a rock shaft 15 journaled in suitable bearings at the rear of the type basket opening 16, and carrying at one end a 85 rocker arm 17 bearing the eccentrically disposed pins 18 at different distances from the axis of the shaft, and coöperating with the separated gear notches 19 at the upper end of one arm of the bell crank operating lever 90 20 pivoted at its angle, as at 21, at one side of the type carriage frame and having a key 22 adjacent to the key-board. The elements 18 and 19 constitute what may be properly termed a mutilated pin gear, which serves 95 to lengthen the leverage of the arm 17, as the rock shaft 15 is turned to an operative position. The rock shaft 15 is provided with an intermediate swinging yoke member 100 23 bearing a head 24 upon which are mounted in spaced relation, the underscoring and canceling elements 25 and 26, respectively. 105

In the lower case position of the platen, when the yoke member or frame 23 is swung up, the underscoring element 25 comes into 110 position so that by releasing the carriages and sliding the same manually, the underscoring will be accomplished. The other auxiliary character 26 will be operable in a similar manner, it being only necessary to 115 shift the platen to its upper case position.

Referring more particularly to the use of a pair of auxiliary characters 25 and 26, it will be observed that the same may consist of revolubly mounted wheels, the periphery of the former carrying a single raised line for underscoring purposes, and the periphery of the latter preferably carrying a plurality of canceling or other characters such as the letter X or individual dot (. . . .) 120 marks, separated dashes (- - - - -), or like characters. Thus the operator, with the right hand depressing the key 22 simply has to actuate the carriage release key and sweep the platen in either direction, to print 125 the underscoring line beneath one or more words, or the canceling or other characters directly across the page or across one or more words, thereby effecting the underscoring or canceling neatly and expeditiously. 130

It will thus be seen that my invention embodies in its organization a normally idle or inoperative key-actuated device or member, carrying an auxiliary character or characters, and having a relative movement to the ribbon in the direction of its length, independently of the movement effected by the ribbon feeding mechanism.

From the foregoing it is thought that the essential features and action of the invention will be readily understood, but it should also be understood that various changes in the form, proportion, and minor details of construction may be resorted to without departing from the scope of the invention or sacrificing any of the advantages thereof.

This application is a division of my aforesaid application No. 221,756, filed August 22, 1904.

20 I claim.

1. In a typewriting machine, a longitudinally movable platen, a ribbon, means, independent of the ribbon feeding mechanism, for moving the ribbon longitudinally with the platen, an auxiliary character, a pivotal support therefor and a key at the keyboard for moving such character into engagement with the ribbon.

2. In a typewriting machine, a ribbon movable with the paper carriage, a revolute member carrying an auxiliary character, a swinging support for said member, and a key in proximity to the type action keys for moving the auxiliary character into printing relation with the ribbon so that a rotatory movement of the member is produced by its engagement with the ribbon.

3. In a typewriting machine, the combination with a paper carriage, a ribbon, a traveling type carriage, an auxiliary character, a swinging support therefor carried with the type carriage and a key in proximity to the type action keys of the machine for moving the auxiliary character into printing relation with the ribbon.

4. In a typewriting machine, a printing ribbon, an auxiliary character, a pivotal support therefor, a key at the keyboard of the machine for moving the auxiliary character into engagement with the ribbon, and means, other than the ribbon feeding mechanism, for imparting a relative longitudinal movement to the ribbon and auxiliary character.

5. In a typewriting machine, a printing ribbon, an auxiliary character, comprising a

wheel member having a printing mark, a pivotal support therefor, a key at the keyboard of the machine for moving the auxiliary character into engagement with the ribbon, and means, other than the ribbon feeding mechanism, for imparting a relative longitudinal movement to the ribbon and auxiliary character.

6. In a typewriting machine, the paper carriage, an auxiliary character consisting of an underscoring mark, a swinging support for said character, and a key at the keyboard operatively connected with said swinging support.

7. In a typewriting machine, the combination with the platen, of a device comprising a rock shaft journaled upon the type carriage frame and carrying an auxiliary character, and an operating key having a variable leverage connection with said rock shaft.

8. In a typewriting machine, the type carriage and the paper carriage having a traveling movement in the direction of letter spacing, and a key-controlled combined underscoring and canceling device carried by the type carriage and including a swinging member or frame bearing underscoring and canceling elements arranged in upper and lower case relation.

9. In a typewriting machine, the type carriage and paper carriage having a movement in the direction of letter spacing, and a key-controlled combined underscoring and canceling device comprising a rock shaft journaled upon the type carriage frame and having a yoke member bearing underscoring and canceling elements arranged in upper and lower case relation, and an operating key having a variable leverage connection with said rock shaft, said variable leverage connection comprising a rocker arm upon the rock shaft carrying eccentrically disposed pins, and a notched gear member carried by said operating key.

10. In a typewriting machine, the traveling type carriage, the traveling paper carriage, and a key-controlled combined underscoring and canceling device having separate revolute underscoring and canceling elements arranged in upper and lower case relation.
